US0D1018982S

(12) **United States Design Patent** (10) Patent No.: **US D1,018,982 S**
(45) Date of Patent: ** Mar. 19, 2024

(54) **EPILATOR**

(71) Applicant: **SkinScience Co., Ltd.**, Seongnam-si (KR)

(72) Inventor: **YoungSan Ko**, Seongnam-si (KR)

(73) Assignee: **SkinScience Co., Ltd.**, Seongnam-si (KR)

(**) Term: **15 Years**

(21) Appl. No.: **29/859,591**

(22) Filed: **Nov. 11, 2022**

(30) **Foreign Application Priority Data**

May 13, 2022 (KR) 30-2022-0019067

(51) **LOC (14) Cl.** **28-03**

(52) **U.S. Cl.**

USPC **D28/44.1**; D24/209

(58) **Field of Classification Search**

USPC D28/44.1; D24/209, 214, 133, 147
CPC A45D 26/0009; A61B 2018/00476; A61B

18/203; A61B 18/18
